SHAPER FOR CUTTING OBOE AND ENGLISH HORN REED CANE

Victor de Marzi, Bronx, N. Y.

Application February 16, 1950, Serial No. 7,966

Term of patent 7 years

(Cl. D54—2)

To all whom it may concern:

Be it known that I, Victor de Marzi, a citizen of the United States, residing at 1058 Southern Boulevard, in the Bronx, county of Bronx, and State of New York, have invented a new, original, and ornamental Design for Shaper for Cutting Oboe and English Horn Reed Cane, of which the following is a specification, reference being had to the accompanying drawing, forming a part hereof.

Fig. 1 is a front elevational view of a shaper for cutting oboe and English horn reed cane, showing my new design;

Fig. 2 is a side elevational view;
Fig. 3 is a sectional view taken on line 3—3 of Fig. 1; and
Fig. 4 is a rear elevational view.

I claim:

The ornamental design for a shaper for cutting oboe and English horn reed cane, as shown.

VICTOR DE MARZI.
